UNITED STATES PATENT OFFICE.

CARLOS F. BENNETT, OF OCEANSIDE, CALIFORNIA.

DESIGN FOR AN AUTOMOBILE RADIATOR ORNAMENT.

Application filed May 7, 1928. Serial No. 26,601. Term of patent 7 years.

To all whom it may concern:

Be it known that I, CARLOS F. BENNETT, a citizen of the United States, residing at Oceanside, in the county of San Diego and State of California, have invented a new, original, and ornamental Design for an Automobile Radiator Ornament, of which the following is a specification, reference being had to the accompanying drawing, forming

a part thereof, in which the figure is a perspective view of the ornament.

I claim—

The ornamental design for an automobile radiator ornament substantially as shown.

In testimony whereof, I have hereunto set my hand at Oceanside, California, this 30th day of April, 1928.

CARLOS F. BENNETT.
